No. 681,001.

Patented Aug. 20, 1901.

A. PAGLIUGHI.

PERPETUAL LEDGER.

(Application filed May 18, 1901.)

(No Model.)

UNITED STATES PATENT OFFICE.

ANTHONY PAGLIUGHI, OF FORT LEE, NEW JERSEY, ASSIGNOR TO GEORGE MCKIBBIN, OF NEW YORK, N. Y.

PERPETUAL LEDGER.

SPECIFICATION forming part of Letters Patent No. 681,001, dated August 20, 1901.

Application filed May 18, 1901. Serial No. 60,808. (No model.)

To all whom it may concern:

Be it known that I, ANTHONY PAGLIUGHI, a citizen of the United States, and a resident of Fort Lee, Bergen county, New Jersey, have **5** invented certain new and useful Improvements in Perpetual Ledgers, of which the following is a specification.

This invention relates to that class of binders known as "temporary" ledgers, and in **10** which any of the leaves may be removed or replaced by first unlocking the binding mechanism.

The invention consists in improved means **15** by which a ready locking and unlocking of said binding mechanism may be effected.

In the accompanying drawings, Figure 1 is a longitudinal section through the binding mechanism of the perpetual ledger on line **20** 1 1, Fig. 3, showing the hooks in engagement with the racks. Fig. 2 is a similar section showing the hooks disengaged. Fig. 3 is a horizontal section on line 3 3, Fig. 4; Fig. 4, a cross-section on line 4 4, Fig. 2; Fig. 5, a detail of the hook and rack, and Fig. 6 a **25** detail of part of the slide *g*.

The letter *a* represents the cover of the book, and *a'* is its flexible back. This back is provided along one side with two rails *b b'*, separated by means of stays *b²*, and along the **30** other side with a single rail *c*. From the inner rail *b'* project three tubes *d d' d*, that telescope corresponding tubes *e e' e*, projecting from rail *c*. The tubes *e e'* are provided on their inner face with teeth to constitute racks **35** *e²*, Fig. 5, which are adapted to be engaged by hooks or pawls *f*, pivoted within tubes *d* at *f'*. The pawls are connected at their upper ends to a slide *g*, movable between the rails *b b'* and guided by means of slots *g'*, which **40** are engaged by some of the stays *b²*. The slide may be moved in one direction by means of a key *h*, inserted through keyhole *h'* of rail *b*, so as to swing the hooks *f* out of engage-

ment with the racks *e²*, Fig. 2. When the key is withdrawn, a spring *j* will return the slide **45** to its normal position and throw the hooks into reengagement with the racks, Fig. 1.

The connection between the slide *g* and the hooks *f* I prefer to make flexible, so as to produce a yielding engagement between hook and **50** rack. To this effect the upper ends of the hooks pass through elongated slots *g²* of slide *g* and are engaged at opposite sides by springs *k* and *l*, attached to the slide.

In order to facilitate the widening of the **55** book, a coiled spring *m* is placed into the central tubes *d' e'*.

The leaves *n* of the ledger are notched or perforated at their rear edge, as usual, so as to embrace the posts *d d' e e'*, to which they **60** are locked by reason of the engagement of the hooks *f* with the racks *e²*. If any of the leaves are to be removed or replaced or new leaves **65** are to be added, the slide *g* is moved, by means of the key, so as to disengage the hooks and permit the telescoping tubes *d e* and *d' e'* to be separated.

What I claim is—

1. A binder provided with telescoping tubes, racks formed within one set of said **70** tubes; hooks passing through the other set of said tubes, and a slide to which the hooks are connected, substantially as specified.

2. A binder composed of a pair of rails, telescoping tubes connected thereto, a slide, hooks **75** yieldingly connected to the slide and projecting through one set of tubes, and racks formed on the other set of tubes, substantially as specified.

Signed by me at New York city, county and **80** State of New York, this 17th day of May, 1901.

A. PAGLIUGHI.
